CLAIM

The ornamental design for a display screen or portion thereof with graphical user interface for podcasts, as shown and described.

DESCRIPTION

The file of this patent contains at least one drawing executed in color. Copies of this patent with color drawings will be provided by the Office upon request and payment of the necessary fee.

FIG. 1 is a front elevational view of a first image in a sequence for a display screen or portion thereof with graphical user interface for podcasts;

FIG. 2 is a front elevational view of a second image in the sequence;

FIG. 3 is a front elevational view of a third image in the sequence;

FIG. 4 is a front elevational view of a fourth image in the sequence;

FIG. 5 is a front elevational view of a fifth image in the sequence;

FIG. 6 is a front elevational view of a sixth image in the sequence; and,

FIG. 7 is a front elevational view of a seventh image in the sequence.

The broken line showing of the display screen and remainder of the graphical user interface forms no part of the claimed design.

(Continued)

The subject matter in this patent includes a process or period in which an image changes into another image. This process or period in which one image transitions to another forms no part of the claimed design.
